UNITED STATES PATENT OFFICE.

JOHN WILLIAM LANDENBERGER, OF PHILADELPHIA, PENNSYLVANIA.

DESIGN FOR WOVEN FABRIC.

SPECIFICATION forming part of Design No. 35,960, dated June 17, 1902.

Application filed May 15, 1902. Serial No. 107,526. Term of patent 3½ years.

To all whom it may concern:

Be it known that I, JOHN WILLIAM LANDENBERGER, a citizen of the United States, residing in the city and county of Philadelphia, State of Pennsylvania, have invented and produced a new and original Design for a Woven Fabric, of which the following is a specification, reference being had to the accompanying drawing, forming part thereof.

10 The drawing represents sufficient of a piece of woven fabric to illustrate the design.

As shown in the drawing, the leading feature of my design consists of a row of stripes *a a*, separated at equal distances and running over the field *b*, the said stripes *a a* being

formed of a series of hollow squares meeting at two of their angles and ornamented at that point by short projecting lines.

Having described my invention, what I claim as new, and desire to secure by Letters 20 Patent, is—

The design for a woven fabric as herein shown and described.

In testimony whereof I have signed my name to this specification in the presence of 25 two subscribing witnesses.

JOHN WILLIAM LANDENBERGER.
